UNITED STATES PATENT OFFICE.

BENJAMIN F. LENTZ, OF SOMERSET, OHIO.

BUTTON-CLASP.

SPECIFICATION forming part of Letters Patent No. 730,136, dated June 2, 1903.

Application filed November 15, 1902. Serial No. 131,524. (No model.)

To all whom it may concern:

Be it known that I, BENJAMIN F. LENTZ, a citizen of the United States, residing at Somerset, in the county of Perry and State of Ohio, have invented new and useful Improvements in Button-Clasps, of which the following is a specification.

This invention relates to a button-clasp; and the object of the same is to provide simple and effective means, forming a part of a button, for holding the latter securely in applied position, and readily assembled in operative relation to a button without requiring a change in the normal structure of the latter.

The invention consists in the construction and arrangement of the several parts, which will be more fully hereinafter described and claimed.

In the drawings, Figure 1 is a perspective view of a clasp shown detached and enlarged and embodying the features of the invention. Fig. 2 is a front elevation of a modified form of the clasp shown on an enlarged scale. Fig. 3 is an elevation of a button embodying the clasp and looking toward the rear side thereof. Fig. 4 is a rear elevation of the button shown by Fig. 3, the back plate or covering removed and showing the clasp in further modified form.

Similar numerals of reference are employed to indicate corresponding parts in the several views.

In all of the forms of the improved clasp a similar body-frame 1 is employed and has a lower reduced extremity 2. This body-frame is formed of resilient wire of a suitable gage, one piece of wire being used and bent to give the body-frame the contour specified. At the lower extremity of the body the wire is inter-twisted, as at 3, and continued upwardly and outwardly to form clasping-arms 4, which movably engage the opposite side portions of the body-frame at a point above the lower reduced extremity of the latter, the arms all having inwardly-bent portions 5 to produce a contracted throat 6, leading to a seat 7, adapted to receive a projecting headed device attached to a garment in either a permanent or removable manner.

The head of the device with which the clasp is adapted to engage has a greater diameter than the maximum distance of the

portions of the arms disposed on opposite sides of and defining the seat 7, so that when said headed device is connected to the clasp 55 disengagement of the button or other device with which the clasp is used will be prevented until manual detachment ensues. The intertwined portions of the wire 3 at the lower terminal of the frame 1 stiffen said 60 part of the frame and cause the arms 4 to more readily return to normal position and resist abnormal bending or misshaping of the arms.

The modification in the structure resides 65 mainly in a different form of engagement of the terminals of the arms 4 with the opposite sides of the body-frame, and secondarily in a difference in the shape of the arms, as shown by Fig. 4, relatively to the arms, as shown by 70 Figs. 1 and 2. In the sides of the body-frame, as shown by Fig. 1, eyes 8 are formed, and therethrough the terminals of the arms 4 movably project. The upper terminals of the arms 4, as shown by Fig. 2, are formed 75 with eyes 9, which slidably embrace the opposite sides of the body-frame 1, and in the form of the device more clearly shown by Fig. 4, but also embodied in Fig. 3, eyes 10 are constructed in the opposite sides of the 80 body-frame 1, (shown by Fig. 1,) and through said eyes 10 the terminals of the arms 4 in Fig. 4 also movably project. The arms 4 (shown by Fig. 4) extend upwardly from the lower intertwist 3 of the wires in converging 85 planes toward the throat 6 and then outwardly through the eyes 10.

As a means for accurately inserting and guiding the headed projecting device adapted to engage the improved form of clasp the 90 button is preferably formed with a back plate or cover 11, having a keyhole-slot 12 in the center thereof, with an enlarged extremity in advance of the throat 6, the maximum diameter of said extremity being slightly larger 95 than the maximum distance between the portions of the arms at opposite sides of the seat 7, so as to easily admit the head of the said projecting device into the button. The opposite extremity of the slot 12 is materially 100 less in width than the said enlarged extremity of the slot and is located over the seat 7. The clasp is almost entirely hidden by the back plate or cover 11, and while the use of

said latter part is advantageous it will be understood that in some instances a button may be provided with the clasp and without the said back plate or cover.

- 5 The improved clasp is intended to be used with advertising and ornamental buttons, as well as buttons bearing insignia of different organizations and societies, and in the general construction of such devices the face of 10 the button is struck outwardly or formed from suitable metal, having a rear inturned flange, as clearly shown by Fig. 4. In assembling the improved clasp with this form of button the upper and lower extremities or ends are 15 sprung under opposite portions of the said flange, and as said opposite ends of the clasp or the body-frame are straight and parallel and one end of said body being of greater extent than the other the arms 4 will always be 20 maintained in one position for convenience in connecting the clasp with a headed device. When the headed device is applied in operative relation to the clasp, it enters between the arms 4 opposite the throat 6, and by pushing 25 the button in the proper direction the shank of the headed projection will be forced through the throat 6 and enter the seat 7. In detaching the button from a headed projection a movement in a direction opposite to 30 that just set forth is imparted thereto.

The improved form of clasp is especially intended for use with cuff-buttons and will

serve efficiently as a convenient means for assembling and disassociating parts of a cuff-button and facilitate application and detachment of the latter. 35

Changes in the proportions, dimensions, and minor details may be resorted to without in the least departing from the spirit of the invention. 40

Having thus described the invention, what is claimed as new is—

1. In a button-clasp the combination of a body-frame having upwardly-projecting outwardly-extending arms contracted at intermediate points to form a throat leading to a seat between the lower portions of said arms, the upper terminals of the arms movably engaging the opposite sides of the body-frame. 45

2. In a device of the class set forth, a body-frame having arms projecting from one end thereof and laterally deflected, the arms having a seat formed between them and providing a contracted throat leading to said seat, the terminals of the arms and the opposite sides 50 of the frame having a loose connecting engagement. 55

In testimony whereof I affix my signature in presence of two witnesses.

BENJAMIN F. LENTZ.
